UNITED STATES PATENT OFFICE.

RICHARD W. MEWES, OF DES MOINES, IOWA.

ENGINE-VALVE.

1,070,829.

Specification of Letters Patent.

Patented Aug. 19, 1913.

Application filed October 26, 1912. Serial No. 728,002.

To all whom it may concern:

Be it known that I, RICHARD W. MEWES, a subject of the King of Great Britain, residing at Des Moines, in the county of Polk and State of Iowa, have invented new and useful Improvements in Engine-Valves, of which the following is a specification.

This invention relates to valve mechanism for slide-valve and other fluid-driven engines, and the primary object of the same is to simplify the construction and lessen the cost of production and maintenance of slide-valve and other fluid-driven engines and at the same time obtain the valuable features and benefits resulting from the automatic balancing and lubricating of such engines by utilizing approximately all of the lubricant applied, in contradistinction to ordinary piston and D-slide valves.

In the improved form of valve embodying the essential features of the invention, all of the lubricant is caused to film between the valve face and the cylinder face and be fully utilized within the cylinder before the steam is exhausted, as opposed to the waste of the lubricant in relative slide valve organizations wherein the bulk of the oil and steam is carried off through the exhaust without having effectively lubricated the most vital parts, namely, the valve and cylinder faces.

In locomotive structures, during the operation of floating or running down grade, the bulk of steam, which is a partial lubricant, being shut off, the improved form of valve, which is grooved and full of lubricant, will continue to automatically distribute or dispense the lubricant from these grooves by the oscillating movement of the valve upon the stationary valve face and casing, without consequent loss in a positive application of the lubricant.

Another valuable feature of the improved valve of the present invention is that it is exempt from the objectionable characteristic of wearing unequally when working extensively, as the wear, if any, is equally divided between the valve face and the cylinder face, whereas in the common D-valve and piston-valve the wear is on the valve face and middle portion only of the cylinder face, thus causing the latter face to assume a concave contour and the valve face to assume a convex shape, and, moreover, the piston valve port bars are also worn concave. Furthermore, the improved valve overcomes the ob-

jectionable tilting motion of the ordinary D-slide valve, as the improved valve has solely an axial movement.

In the manufacture of the improved valve no special tools are required, as all the work can be accomplished by means of a lathe, which economy in the production of the valve will be of material advantage in the installation and use of the same, and at the same time the important features of positively balancing and automatically lubricating the valve are obtained by a simple primal structural operation. Furthermore, the externally exposed surface of the valve is very much less in area than in analogous valves, and consequently the condensation of steam is materially reduced during the travel of the steam and the use of less fuel and water correspondingly ensues. The improved valve may also be placed or applied on the under side or bottom of the cylinder, if desired, and in which position it will automatically carry off all condensed steam accumulating adjacent thereto at each stroke of the piston, and thus keep the piston free from obstruction without lessening the pressure in the cylinder through the operation of opening blow-cocks, etc.

Another important advantage of the improved valve over the ordinary piston-valve is that it does not have the enormous waste of power and steam on the gearing in overcoming the inertia or endwise to-and-fro motion which the heavy piston-valve imposes upon the gearing, especially when running at high speed, because the improved valve moves in a balanced manner, or one-half moves one way while the other half moves the opposite way, in contradistinction to the bodily movement of piston-valves and D-valves in opposite directions, and by this means the inertia to be overcome is reduced to a minimum, especially when the bridge bars of steam ports are worn.

A still further structural advantage of the improved valve is that there are no rings to collapse while under compression and cut-off and therefore a much cleaner and more accurate compression and cut-off can be obtained and the good characteristics or valuable features of the old form of D-slide valve are preserved in the present structure together with a positive balance and self-lubrication.

The valve is of such simple structure and

may be so readily replaced that it is proposed to have the improved valve and cases in quantities always kept ready or in stock for substitution for corresponding worn out parts at a materially reduced expense and without loss of time in maintenance.

With these and other objects and advantages in view the invention consists in the construction and arrangement of the several parts which will be more fully hereinafter described and claimed.

In the drawings: Figure 1 is an enlarged longitudinal vertical section of the improved valve and its casing and a corresponding cross-section of a portion of the cylinder. Fig. 2 is a section taken in the plane of the line 2—2, Fig. 1.

In said drawings, A indicates, generally, the cylinder of a steam or other fluid-driven engine, B the steam chest, and C the valve. The part A is of the usual construction, and is provided adjacent its opposite ends with the passage 2, leading into the interior of the valve casing 3. Steam or other motive fluid is admitted into the steam chest B in any suitable manner, and passes therefrom to the valve by way of the inlet passage 5, and thence either to the cylinder through the passage 2, or to the exhaust pipe (not shown) by way of the passage 7, as hereinafter described. The valve casing, and the valve 8, which it contains, are slightly tapered, the said valve being designed for backward and forward rotary movement through the agency of a suitable valve gear (not shown). This valve is provided at opposite ends with trunnions or stems 9 and 10, which are mounted in suitable bearings, and it is preferably hollow, as shown, and is formed with the opposed ports 11 and 12 that open into its interior, and also, with an arcuate cavity or passage 13. The port 11 registers with the outer end of the inlet passage 5, and has sufficient width to remain in registration therewith, during the entire movement of the valve; the port 12 is brought into and out of registration with the passage 2; while the cavity 13 is designed to bridge communication between the passage 2, and exhaust passage 7, at the proper times.

To provide for automatic lubrication of the valve and the cylinder face, the upper portion of the valve casing is formed on its inner face with an oil chamber 32, to which the oil, or other lubricant, is supplied by a suitable pipe or pipes 33. The ends of the valve terminate short of the end walls of the casing, thus providing a pair of auxiliary lubricant chambers 34 which are filled from the chamber 32, and, therefore, the lubricant will be caused to film through the adjacent passage 2 into the cylinder, around the inner surface of which it spreads, and it will also film through the passages 5 and 7.

This filming takes place, as will be understood, between the faces of the valve and its casings, and since the lubricant enters and spreads into the cylinder in film form, it will not be blown out with the exhaust steam, as would be the case if it were dropped or otherwise introduced bodily in separate masses into the cylinder. In this way, perfect lubrication is insured and waste avoided.

As hereinbefore stated, the inlet port 11 has sufficient width to remain in registration with the inlet passage 5 during the entire movement of the valve. This is a matter of special importance, as will be seen from the following:—In many high speed steam engines, as ordinarily constructed, the steam is exposed to blasts of cold air which is intensified by the high speed of travel. As a result, enormous condensation takes place, and the body of live steam in the steam chest is not at the proper temperature to enter the cylinders when the valves open quickly, thus increasing wear and the consumption of fuel and water, particularly in cold weather. On the other hand, by maintaining the interior of the valve in constant communication with the steam chest, the valve is always filled with steam at the same temperature which thus prevents condensation and water accumulation, and, in consequence, pounding of the valves and pistons. Moreover, by providing what is in effect a solid roof in the valve itself between the inlet and outlet ports and directly above the bridge, the pressure of the steam confined in the valve is exerted upwardly in a direction diametrically opposite the passages 2 and 7. In this way an approximately perfect balance of the valve is insured, as long as the steam supply is "on", and when the steam is cut off, (as, for instance, when the locomotive is floating), the valve loses this function, but retains that of automatically lubricating itself.

Having thus described my invention, what I claim is:

1. The combination of a valve-casing having a lubricant chamber in its upper portion, and lubricant supply means in communication therewith; a rotary valve disposed within said casing, the ends of said valve terminating short of the end walls of the casing, to produce auxiliary lubricant chambers; and means for operating said valve.

2. The combination of a valve casing formed with steam inlet and outlet passages, and with a passage located adjacent the outlet passage, all of said passages opening into its interior; an oscillatory valve disposed within said casing and having a pair of opposed ports co-operative with the inlet and last-named passages, and a cavity movable into and out of position to bridge communication between said last-named passage and

the outlet passage, the port coöperative with said inlet passage being sufficiently wide to remain in communication therewith during the entire movement of the valve; and means 5 for operating said valve.

3. The combination of a valve casing formed with a lubricant chamber in the upper portion of its inner face, and with steam inlet and outlet passages and a passage located adjacent the outlet passage, all of said 10 passages opening into the interior of said casing; an oscillatory valve disposed within said casing and having a pair of opposed ports coöperative with the inlet and last- 15 named passages, and a cavity movable into and out of position to bridge communication between said last-named passage; lubricant supply means in communication with said chamber; and means for operating said 20 valve.

4. The combination of a valve formed with a lubricant chamber in the upper portion of its inner face, and with steam inlet and outlet passages and a passage located 25 adjacent the outlet passage, all of said passages opening into the interior of said casing; an oscillatory valve disposed within said casing and having its ends terminating short of the end walls of the casing, to produce auxiliary lubricant chambers, said 30 valve being provided with a pair of opposed ports coöperative with the inlet and last-

named passages, and a cavity movable into and out of position to bridge communication between said last-named passage and the 35 outlet passage; lubricant supply means in communication with the first-named chamber; and means for operating said valve.

5. The combination of a valve casing formed with a lubricant chamber in the upper portion of its inner face, and with steam inlet and outlet passages and a passage located adjacent the outlet passage, all of said 40 passages opening into the interior of said casing; an oscillatory valve disposed within 45 said casing and provided with a pair of opposed ports coöperative with the inlet and last-named passages, and with a cavity movable into and out of position to bridge communication between said last-named passage 50 and the outlet passage, the port coöperative with said inlet passage being sufficiently 55 wide to remain in communication therewith during the entire movement of the valve; lubricant supply means in communication with said chamber; and means for operating said valve.

In testimony whereof I have hereunto set my hand in presence of two subscribing witnesses.

RICHARD W. MEWES.
